UNITED STATES PATENT OFFICE.

HATTIE C. LESLIE, OF DUQUESNE, PENNSYLVANIA.

DESIGN FOR LINOLEUM.

42,582.

Specification for Design.

Patented June 4, 1912.

Application filed April 6, 1912. Serial No. 689,088. Term of patent 7 years.

To all whom it may concern:

Be it known that I, HATTIE C. LESLIE, a citizen of the United States, residing at Duquesne, in the county of Allegheny and State of Pennsylvania, have invented a new, ornamental, and original Design for Linoleum, of which the following is a specification.

Reference is had to the accompanying drawing, in which: the figure is a plan view showing my new and ornamental design for linoleum.

I claim:

The ornamental design for linoleum, as shown.

In testimony, that I claim the foregoing as my own, I have hereto affixed my signature in the presence of two witnesses.

HATTIE C. LESLIE.

Witnesses:

FRED GERDTS,
MARY PINDEL.
